CHARLES G. FAIRCHILD, OF BROOKLYN, NEW YORK.

DOOR-CHECK.

1,149,902.

Specification of Letters Patent.

Patented Aug. 10, 1915.

Application filed February 21, 1913. Serial No. 749,785.

To all whom it may concern:

Be it known that I, CHARLES G. FAIRCHILD, a citizen of the United States, residing at Brooklyn, in the county of Kings and State of New York, have invented certain new and useful Improvements in Door-Checks, of which the following is a full, clear, and exact description, such as will enable others skilled in the art to which it appertains to make and use the same.

This invention relates to door checks, and with regard to certain more specific features, to a device adapted to retard the closing movement of a swinging door.

One object within the contemplation of this invention is to provide a reliable and practical checking mechanism in which the retarding features of the expensive and troublesome devices now in use are retained and improved upon without the many obvious disadvantages attendant upon the use of such devices.

Another object is to provide an inexpensive and easily constructed device of the specified nature for positively and effectively checking the closing movement of a door, whether said movement be due to wind pressure, to closing devices such as springs, to manual force, or to a combination of these agencies.

Another object is to provide an arrangement of parts whereby a retarding element performs half its cycle of operation to check the momentum of the closing door, and then completes its cycle of operation as the door approaches its closed position, all with little or no strain upon the hinge members of the door.

Another object within the scope of the invention is to provide a simple, reliable and easily constructed checking mechanism adapted to exert no opposition whatever to the opening movement of the door.

Another object is to provide a device of the character described which effectively prevents the slamming of the door and yet diminishes in no way the closing action of the springs or other agency while the door is shut, whereby the door may be kept closed even against a considerable wind pressure without the use of latches.

Other objects will be in part obvious and in part pointed out hereinafter.

The invention accordingly consists in the features of construction, combinations of elements and arrangement of parts which

will be exemplified in the construction hereinafter set forth, and the scope of the application of which will be indicated in the following claims.

In the accompanying drawings, in which are illustrated one or more of various possible embodiments of the several features of the invention,

Figure 1 is a plan view, partly diagrammatic, of a preferred form of checking mechanism located, in this case, adjacent the top surface of the door and viewed from beneath; Fig. 2 is a detail plan view on a larger scale of the cushion device and associated parts shown in Fig. 1, portions being broken away to show more clearly the interior structure; and Fig. 3 is an elevation corresponding to Fig. 2, with parts shown as in a section taken on line 3—3, Fig. 1.

Similar reference characters refer to similar parts throughout the several views of the drawings.

Referring now more particularly to Fig. 1, there is illustrated in the walls 1 an opening adapted to be closed when desired by the door 2, shown in the present instance as adapted to swing on the vertical hinges 3 from a position 4 of rest against the jamb 5 to or beyond a position 6 to be designated, for convenience, as the open "position" of the door, although it is obvious that the movement of the door is not necessarily restricted to the angle 7 subtended by the planes 4, 6 at the hinges 3. Closing means (forming in themselves no part of the present invention) such as a weight, or a non-vertical arrangement of the door, or preferably the springs illustrated conventionally at 8 tend at all times during normal operation to cause the door to close or maintain it in its closed position, as the case may be. By virtue of certain features of the invention to be set forth in detail later on I am enabled to use in connection with the checking mechanism, springs 8 of considerable power, so that the door may be retained in its closed position by the springs alone without the necessity of providing the customary latches.

The checking mechanism *per se* comprises a member located, in the present instance, on the lintel and adapted to coöperate at predetermined times with a second member secured to the door. For reasons that will appear as the description proceeds, I prefer to mount the parts as indicated, although

the relative locations thereof may be interchanged without departing from the spirit of the present invention. The door member comprises simply a projection 9 extending 5 inwardly from the plane of the door from a point adjacent the top surface thereof and is located preferably close to the vertical plane at right angles to the door and passing through the center of mass thereof; the projection 10 is secured to the door as at 10, 11 by set screws or other suitable retaining means. This projection 9 is preferably sufficiently strong and so braced that its end 12 will not be distorted from its initial position with 15 respect to the door by the stresses occurring during the operation of the checking device. In operative engagement with the end 12 of the projection 9 during the latter part of the closing movement of the door is the element 20 13 (Figs. 2 and 3) fixed to the movable member of a suitable checking device such as the rod 14 secured to the piston head 15 which reciprocates within the cylinder 16 filled with a fluid (such as oil or air) and 25 provided with suitable means for restricting the passage of fluid into or out of the respective portions of the cylinder. A regulator adapted to restrict the flow to the desired extent is shown in the present instance 30 as comprising a tubular by-pass 17 connected with either end of the cylinder 16 and adapted to be almost entirely closed throughout the desired portion of its length by the screw-threaded member 18 co-axial with the 35 tubular by-pass 17. Lock nuts or other suitable locking devices are provided to maintain the screw-threaded member 18 in its adjusted position. The fluid in order to pass through the tube 17 from one end of 40 the cylinder to the other must pass around or over a predetermined adjustable number of turns of the screw-threads of the member 18, and I have found that an effective resistance is offered to the passage of the fluid 45 not only by virtue of the tortuous path around the screw-threads but by the friction resulting from the confluence of the fluid streams passing respectively over and along the screw-threads. Needless to say, the device 50 is capable of precise adjustment, if necessary, in the manner well known in micrometers. The checking piston device 19, comprising the rod 14, piston head 15, cylinder 16 and by-pass device 17, 18, is mounted 55 to swing as a whole about a vertical pivot 20 against the action of the spring 21 from a position of rest against the adjustable stop 22. It may be stated at this point that if 60 the door is intended to swing in the opposite direction to that shown in the drawings, the only changes needed in the checking mechanism are to reverse the connections of the spring 21 so that the position of rest of the checking device 19 will be against the 65 stop 23 instead of against the stop 22.

The element 13, which partakes of course of the rectilinear movements of the piston rod 14, is shaped in such a way as to engage the end 12 of the projection 9 from the time the door completes at the position 24 the first 70 portion 25 of its closing movement until the door is entirely shut. This angular travel 26 may be sub-divided for convenience into three angular displacements 27, 28, 29 termed respectively the second, third and 75 fourth portions of the closing movement. During the first portion 25 the door closes under the action of the springs 8 unopposed by the checking mechanism. At the end of the first portion 25, that is, at the line 24, the 80 end 12 of the projection 9 fixed with respect to the door 2 engages the concave part of the element 13 secured to the piston rod 14; a piece of leather or other noise-deadening device (not shown) being attached, if desired, to the projection 9 or to the element 13 or to both; at this time, as will be clear from Fig. 1, the piston device is held parallel to the projection 9 and therefore normal to the plane of the door by the spring 21 90 urging the checking device 19 against the adjustable stop 22. The continued closing of the door results in the rectilinear movement of the rod 14 toward the pivotal point 20 of the checking device 19, as well as in 95 the rotation of the checking device as a whole about said pivotal point away from the stop 22 in opposition to the force exerted by the spring 21, the movement of the end 12 of the projection 9 at an increased 100 angle 30 to the rod, comprising a component parallel to the piston rod effective in pushing in the rod and a component at right angles thereto by virtue of which the checking device 19 as a whole rotates about the pivotal 105 point 20.

At the initial position 24 of engagement, and for an appreciable angular travel thereafter, the angle 30 is so small that the resisting power of the checking device, exerted 110 in a direction practically normal to the door, is all effective in checking the movement of the door, with the result that a cylinder of comparatively small resisting power is 115 amply sufficient to retard the motion of the door to the necessary extent. An obvious advantage gained by this first retardation is that the door is automatically prevented from catching the heels of a person passing through, a feature noticeably lacking in 120 many devices that complete the closing movement of the door without undue delay. As the second portion 27 of the movement progresses, the increasing angle 30 between the projection 12 and the piston rod 14 results in less opposition to the movement of the door, together with a greater angular 125 velocity of the checking device 19 about the pivot 20. At the end 31 of the second portion 27 the rod 14 has completed its inward 130

rectilinear stroke, the checking device has rotated to the position indicated in Fig. 1, the end 12 of the projection 9 has advanced to the other end of the concave part of the 5 element 13 and the door closes unimpeded by any opposition on the part of the checking device. This unobstructed travel of the door takes place, of course, at an increased speed and the door quickly reaches the end 10 32 of the third portion 28 of its closing movement, where the rod 14 is about to be pulled outward away from the pivot 20 by the force exerted by the projection 9 at the now obtuse angle 30 to the rod 14. From 15 this point 32 throughout the fourth portion 29 of the closing movement the checking force increases, due to the increase of the angle 30, and as a consequence the speed of the door is positively and effectively reduced 20 to a predetermined and sufficiently low value as the door reaches its final position against the jamb 5. When the motion of the door has ceased, and as long as the door remains closed, the full force of the springs 8 un- 25 diminished (save for the negligible action of the spring 21) by any action of the checking apparatus is effective to hold the door shut. By making these springs of consider- 30 able power, which can readily be done without impairing the retarding efficiency 35 of the checking mechanism, it becomes unnecessary to provide a latch or other lock to keep the door closed.

When the door is opened from its closed 35 position, the end 12 of the projection 9 fixed to the door describes the arc of a circle, indicated at 33 (Fig. 1), and almost instantaneously rides out of the concave portion of the element 13 to the point 34 on this arc. 40 Owing to the magnitude of the angle 30 and to the fact that the smooth surface 35 of the projection 9 slides readily past the abutment 36 of the element 13, the end 12 of the projection 9 reaches the position 34 without exerting sufficient force upon the element 13 to move the latter rectilinearly inward toward the cylinder 16; the movement of the element 13, if it have any during this slight angular travel outward of the door 45 2, comprises an almost negligible clockwise rotation, together with the rod 14 and other elements of the checking device 19 about the pivot 20 as a center, in opposition to the force exerted by the spring 21. When the end 12 of the projection 9 has reached the position 34, it will then simply ride inwardly over the surface 37 of the element 13 and over more or less of the rod 14, according to the proportions employed in 50 actual practice for the several parts of the apparatus, the element 13 and rod 14 being held against the end 12 of the projection 9 by means of the coil spring 21. When the door has opened to approximately the position 32, the end 12 of the projection 9

will begin to slide outwardly along the rod 14 and then along the surface 37 of the element 13, the piston continuing to rotate counter-clockwise (Fig. 1) under the influence of the spring 21 until the door is 50 opened beyond the position 24, after which time the checking device rests against the stop 22 with the rod 14 extended and the element 13 ready to engage the end 12 of the projection 9 when the door again closes 75 to the position 24. The opening of the door, it is noted, involves no rectilinear movement of the rod 14 and hence no more effort is required to open the door than would be needed if the check were not used. If the 80 door is opened only part way or is closed only part way and then opened again, the arrangement and design of parts is such that after practically every combination of movements (except a movement from the 85 closed position throughout an angle less than the angle 29) the door when released will close with a final velocity substantially the same as in the closing operations described in detail above. If, for example, the piston 90 head 15 is not at the outer end of its travel, but is adjacent the inner end of the cylinder 16, the end 12 of the projection 9 will strike the extension 33 of the element 13 some time during the second portion 27 of the closing 95 movement; the end 12 will then slide upon the surface of this extension 27 into the concave part of the element 13 and the third and fourth portions of the closing movement will take place as before. 100

By virtue of the double stroke of the piston or other cushion device (during the second and fourth portions of the closing movement) instead of a single stroke, not only is it unnecessary to force the piston head toward or away from the pivot 20 during the opening of the door, but the cylinder need be only half the ordinary size to do a given amount of work. 105

A corollary advantage is gained by an arrangement such as the present one which allows a check of small dimensions to be actuated by a door-carried element throughout a considerable travel of the door. This advantage resides in having the resisting power of the check applied to the door at a point remote from the hinges, such as a point substantially in the vertical line through the center of mass of the door. It will be clear that this arrangement allows 110 the resisting power of the check to be applied to the door so that no amount of momentum of the door however great, will cause the lateral strain on the hinges that is necessarily incident to the operation of 115 any checking mechanism that acts on the door at a point near the hinges. 120

It will thus be seen that there is provided an apparatus in which the several objects 125 of this invention are achieved and in which 130

the above and other advantages are obtained.

As many changes could be made in the above construction, and many apparently 5 widely different embodiments of this invention could be made without departing from the scope thereof, it is intended that all matter contained in the above description or shown in the accompanying drawings shall be interpreted as illustrative and 10 not in a limiting sense.

Having described my invention, what I claim as new and desire to secure by Letters Patent is:

15 1. Apparatus of the character described comprising, in combination, a door, means normally tending to close the door, and means comprising a retarding device provided with members, said device being arranged to provide relative movement in two 20 directions of said members and effective to permit the unobstructed action of said closing means during the first part of the closing movement of the door and to retard the 25 door during the latter part of said closing movement by said relative movement in two directions of said members.

2. Apparatus of the character described comprising, in combination, a door, and a 30 device mounted partly on the lintel and partly on the door and adapted to retard the closing movement of the door by virtue of the relative movement of retarding portions of said device, said device being adapted 35 during the closing movement of the door to bring said retarding portions into their proper position relative to each other to retard the next closing movement of the door, the part on said lintel and the part on said 40 door being separated from each other when the door is sufficiently open.

3. Apparatus of the character described comprising, in combination, a door, means normally tending to close the door, and 45 means located partly on the lintel and partly on the door comprising a piston adapted to retard the closing of the door by both its inward and outward motion, the part on said lintel and the part on said door 50 being separated from each other when the door is sufficiently open.

4. Apparatus of the character described comprising, in combination, a door, means normally tending to close the door, and 55 means comprising a piston arranged for movement in two directions and moving and retarding by a single stroke in each direction during the closing movement of the door, whereby said means is adapted to retard the 60 closing movement of the door during two portions of said movement, said means exerting no opposition to the opening of the door.

5. Apparatus of the character described 65 comprising, in combination, a door, a re-

tarding device comprising a piston and a cylinder adapted to retard the rectilinear movement of said piston, and means whereby said device rotates bodily and said piston moves rectilinearly with respect to said cylinder during the closing movement of the door, the device rotating bodily but the piston maintaining its position with respect to the cylinder during the opening movement of the door.

6. Apparatus of the character described comprising, in combination, a door, a retarding device comprising a piston and means adapted to retard the rectilinear movement of said piston, and means whereby said device rotates bodily and said piston moves rectilinearly in one direction and then in the reverse direction during the closing movement of the door, said second means being adapted to effect the return rotative movement of the device during the opening of the door but to obviate the rectilinear movement of the piston during the opening of the door.

7. Apparatus of the character described comprising, in combination, a door, means normally tending to close the door, a piston, means adapted to retard the rectilinear movement of said piston, and means whereby said piston moves rectilinearly during the closing movement only, the initial rectilinear movement of said piston being exerted in a direction substantially normal to the plane of the door.

8. Apparatus of the character described comprising, in combination, a door, means located on the lintel comprising a piston and a device adapted to retard the rectilinear movement of the piston, means on the door adapted to engage said piston and move it rectilinearly in both directions during the closing movement of the door, and means for returning said first means during the opening movement of the door to position for engagement with said second means, said second means acting in opening without causing rectilinear movement of the piston.

9. Apparatus of the character described comprising, in combination, a door, a retarding device comprising a piston, means for rotating said device, and for moving the piston head within the cylinder during the closing movement, and means for effecting the return rotative movement of said device during the opening movement of the door, said piston head maintaining its position within the cylinder during said opening movement.

10. Apparatus of the character described comprising, in combination, a door, means normally tending to close the door, and a device mounted partly on the lintel and partly on the door and comprising a piston acting in both directions to retard the closing of the door and adapted to exert no opposition to the opening of the door, the part

on the lintel and the part on the door being separated when the door is sufficiently open.

11. Apparatus of the character described comprising, in combination, a door, means normally tending to close the door, and a checking device including a piston adapted to retard the latter portion of the closing movement of the door by both the inward and outward motions of said piston, the device being ineffective during the opening of the door and likewise ineffective during the first part of the closing movement of the door.

12. Apparatus of the character described comprising, in combination, a door, means comprising a piston and a device adapted to retard the rectilinear movement of the

piston, means adapted to engage said piston and move it rectilinearly in both directions during the closing movement of the door, 20 one of said means being located on the lintel and the other on the door, and means for returning said first means during the opening movement of the door to position for engagement with said second means, said 25 second means acting in opening without causing rectilinear movement of the piston.

In testimony whereof I affix my signature, in the presence of two witnesses.
